UNITED STATES PATENT OFFICE.

WILLIAM F. ENGLEBRIGHT, OF NEVADA CITY, CALIFORNIA.

MINER'S-INCH WEIR.

1,042,097.

Specification of Letters Patent.

Patented Oct. 22, 1912.

Application filed February 8, 1912. Serial No. 676,422.

To all whom it may concern:

Be it known that I, WILLIAM F. ENGLEBRIGHT, a citizen of the United States, residing at Nevada City, in the county of Nevada and State of California, have invented new and useful Improvements in Miner's-Inch Weirs, of which the following is a specification.

This invention relates to water measuring apparatus and particularly to an improved miner's inch weir.

The object of the present invention is to provide an improved means whereby the volume of a flowing stream may be accurately measured at all times.

It is a special object of the invention to devise an improved plate, board, or dam having a discharge opening of such configuration that the volume of water flowing through will increase substantially in direct proportion to the increase of head in the stream across which the measuring device may be erected practically combining the miner's inch and weir methods of measuring water.

Heretofore running streams of water, the volume of which it is desired to measure, have been caused to flow through openings in a dam or board under a given pressure whereby the volume of water is measured by the number of square inches in the opening; this system being known as the "miner's inch" measurement. The volume of water flowing through a rectangular opening is calculated by the well known formula

$$V = 8.03C\sqrt{H}$$

in which V =number of cubic feet per second; H =depth of water in feet above center of opening; A =area in square feet of opening; C =a variable coefficient determined by experiments. If the opening is in a thin vertical partition, giving full contraction of the stream with different sized openings and different pressures, this coefficient varies as shown by experiment from .56 to .70. If the partition has material thickness and the edges of the opening are rounded or beveled this coefficient may under different conditions vary from .56 to .95 changing with length and height of the opening, pressure of water and shape of the edges of the opening. The volume of water flowing through a rectangular opening is increased as the pressure increases. But the proportionate

increase of flow decreases as the depth increases. Another well-known system of measuring running water is the weir which comprises a simple dam or board adjusted across a stream so that under a given head of water in the stream a given volume of water will discharge over the weir of given length. The volume of water flowing over a weir is calculated by the well known formula

$$V = CL\sqrt{H^3}$$

in which V =number of cubic feet per second; L =length of the weir in feet; H =depth of water in feet above the edge of the weir taken to a horizontal level of still water up stream; C =a variable coefficient determined by experiment. Ordinarily the coefficient C is taken at 3.333, but it must be corrected and allowance made to suit velocity of approach of the stream, for distance of edge of weir above the bottom of the channel and for contraction of the stream at ends of the weir. In short weirs the effect of this contraction of the stream is important and may be compensated for by making the ends of the weir divergent upward. If the weir plate has material thickness the effect of end contraction of the stream may be partially compensated for by rounding or beveling the edges of the ends of the weir. The proportionate volume of water flowing over a weir is increased as the depth increases.

Users of water in certain regions are required to provide means for measuring the water and are often required to figure the proportions of weirs or miner's inch devices in order to determine the volume of water which will run past the apparatus under given conditions, and the mathematics involved in these calculations are often unknown to the operators and are difficult to obtain by them.

It is one of the objects of this invention to devise and provide an improved water measuring apparatus which is of such simple construction that with the knowledge of one factor, for instance a coefficient, and having a given head of water, the coefficient multiplied by a given head of water will instantly give the volume of water discharged through the measuring device.

It is evident with these two systems of measuring water, in each of which condi-

- tions and shapes of openings may be varied, where in one the proportionate volume of water decreases and in the other it is increased as the depth of water is increased, that the two systems can be combined to give a resulting flow so that the volume of water passing through the combined openings will increase in direct proportion as the depth increases.
- 10 The invention consists of the parts and the construction and combination of parts as hereinafter more fully described and claimed, having reference to the accompanying drawing, in which the figure is a perspective view of the improved miner's inch weir board as attached to a flume.
- 15 I have experimented with and devised a form of measuring board or dam 2 in which there is formed a peculiarly shaped orifice, 20 which is here indicated substantially in the form of an inverted letter T; the lower portion 3 of the orifice being a rectangular opening having a length greater than its height and of such dimensions as may be necessary 25 to permit any desired quantity of water to pass through it, said orifice having in the form shown in the drawings, upper and lower parallel and equal walls and parallel and equal vertical ends, forming a horizontal 30 mouth resembling a miner's inch measure for the discharge of water from the stream, flume, sluice, or other supply source, indicated at A, from which it is desired to derive a certain volume of water or other 35 fluid. Suitably disposed with relation to the horizontal opening 3 in the dam 2 is another opening, as 4, which may connect or intersect with the portion 3, and which partakes of the nature of a contracted weir; 40 the openings 3 and 4 being designed to work in harmony and practically combining two different methods of measuring water, some of the lines of the openings 3 and 4 being slightly curved or reverse curved to suit 45 different conditions.
- It is manifest that the combined area of the opening or openings represented at 3-4 may be varied in different plates or dams 2 to accommodate the discharge of 50 large or small quantities of water from different or certain streams, and the gist of the invention resides in so designing the opening or openings through which the water issues from the dam 2 that for every 55 variation in the level of the water in the canal or flume there will be a decreased or an increased volume of water discharged from the dam in direct proportion to the rise or fall of the head in the main conduit.
- 60 Having ascertained the desired configuration of the discharge opening in the dam 2, and having determined a coefficient of discharge under a given head of water through the peculiar discharge opening in the dam 2, then as the water head rises or

falls this coefficient, when multiplied by the head, is designed to give a product indicating the cubic feet or other desired unit of measure in a certain period of time. For instance, if there be a discharge opening, indicated at 3-4, in the dam 2 of certain configuration and having a given coefficient of flow at a given head, then a rise in the head of water in the main supply conduit A should give a direct proportionate increase in volume for the increase in head, and conversely for a decrease of head of the water there should be a proportionate decrease of volume discharged through the dam 2. Hence it will be seen that I can provide dams 2 having a certain discharge opening or openings to be employed under given conditions, and by marking on the dam 2 a factor or coefficient for this particular style of dam then the operator purchasing and using the same merely ascertains the head of water in the supply canal and multiplies this by the coefficient of which he is informed or which he finds marked on the dam 2, the product of the coefficient and head giving him the volume of water flowing through the dam. Manifestly, as stated, the configuration of the discharge opening in the dam 2 will be determined as expediency requires, and while it is shown in the present instance as having an inverted substantially T-shaped form, the vertical part of it has slightly curved sides, as shown, forming the opening area 4.

The coefficient of each particular dam, depending upon the area and configuration of the opening, may be marked on the face of the dam, as indicated at C, or may be provided in any other method sufficient to inform the operator of the value of the factor. With this information by simply measuring the head of water in the supply canal, as A, he can readily ascertain the volume discharged.

If desired, one face of the dam 2 may be provided with projecting graduations 5 representing the volume of water flowing through the dam at any head. Another means for indicating the head of water and volume is indicated as comprising a well or chamber 6 communicating with the water in the canal A through a suitable duct or aperture 7 which allows the water to rise in the well 6 so that the surface level of the water can be ascertained by a hook gage 8 attached to a slide 9 movable over a scale beam 10, having graduations 11 at one part representing a unit of height of water in the canal and other graduations, as 12, representing the volume of water flowing through the dam 2 at a given head in the canal per unit time. The chamber 6 containing the hook gage 8 may be erected adjacent to the canal A or at some distant point, as in a building or office, so long as the chamber 6 is in com-

munication with the canal A so that water may rise in the chamber 6 to the same level as that in the canal A.

While the indicator 9-10 affords a means 5 of indicating the volume and head, it is desirable to provide an automatic recording apparatus, and I have shown this as including a well or chamber 15 connected to the canal or flume A by a pipe or conductor 10 16 which extends into the flume and permits the water to rise in the chamber 6 to the level of the water in the flume. Disposed in the chamber 15 is a float or other suitable device 17 connected by a rod 18 15 to a lever 19 fulcrumed at 20; the lever actuating a marking device or pencil 21 which may rest upon the surface of a dial or recording sheet 22 movable by a clock structure or other apparatus indicated at 23.

20 The advantage of the self-recording device, consisting of the float 17 and its associated elements, is that by this means a constant and reliable record is made of the volume of water being discharged through 25 the dam 2. For each variation of level of water in the main supply canal or flume A there is a corresponding variation in the chamber 15; this variation affecting the vertical position of the float 17. This motion 30 is transmitted from the float 17 by the link 18 and lever 19 to and recorded by the pencil 21.

The dam 2 may be made of any suitable material and may be mounted to form a 35 water-tight joint at any suitable point in the main supply reservoir or canal desired.

It may be desirable to use a gage plate having projecting graduations, as 25, which may be placed at a suitable point in the main 40 supply, this gage being graduated to indi-

cate volume of water passing through the dam at any head.

Having thus described my invention, what I claim and desire to secure by Letters Patent is—

1. In a water measuring apparatus, a dam 45 designed to discharge a volume of water proportionately increasing or proportionately decreasing with a rise or fall respectively of head on the supply side of the dam, said dam having an upper vertical and a lower horizontal orifice, said vertical orifice having curved walls which converge toward and connect with the horizontal orifice and said horizontal orifice having a uniform 50 vertical height and having a horizontal length in excess of the vertical height.

2. In a water measuring apparatus, a dam 55 designed to discharge a volume of water proportionately increasing or proportionately decreasing with a rise or fall respectively of head on the supply side of the dam, said dam having two orifices one of which is vertical and the other horizontal, the horizontal orifice having parallel top and bottom 60 walls, and the vertical orifice having walls curved in the direction of the greatest length of the orifice and with one wall curved in one direction and the other curved in the opposite direction, whereby the maximum 65 width of the vertical orifice is at a point intermediate of the ends of the orifice.

In testimony whereof I have hereunto set my hand in the presence of two subscribing witnesses.

WILLIAM F. ENGLEBRIGHT.
